UNITED STATES PATENT OFFICE.

CHARLES C. TANNERT, OF BROOKLYN, NEW YORK.

TOP-SPINNING DEVICE.

971,420.

Specification of Letters Patent. Patented Sept. 27, 1910.

Application filed March 27, 1908. Serial No. 423,691.

To all whom it may concern:

Be it known that I, CHARLES C. TANNERT, a citizen of the United States, residing at Brooklyn, in the county of Kings and State 5 of New York, have invented new and useful Improvements in Top-Spinning Devices, of which the following is a specification.

This invention relates to a device for spinning tops of that character consisting of a 10 cord on which is freely movable a button or winder for permitting the cord to be readily wound on the top at the required tension and at great speed without the fingers becoming sore by the passage of the cord over the fingers, according to the ordinary way of winding a top.

The invention has for one of its objects to provide a device of this character which is comparatively simple and inexpensive to 20 manufacture, and highly effective in use.

A further object of the invention is the provision of a top spinning device consisting of a cord knotted at both ends and on which is a winder or button having a passage 25 through which the cord passes with sufficient friction to insure the winding of the cord on the top at the required tension, the button serving as a handle used in the winding of the cord and as a grip while throwing 30 the top in the spinning operation.

With these objects in view and others, as will appear as the description proceeds, the invention comprises the various novel features of construction and arrangement of 35 parts which will be more fully described hereinafter and set forth with particularity in the claim appended hereto.

In the accompanying drawing, which 40 illustrates one of the embodiments of the invention, Figure 1 is a perspective view of the device. Fig. 2 is a central longitudinal section of the winder. Fig. 3 is a detail view showing the manner of using the device.

Similar reference characters are employed 45 to designate corresponding parts in the views.

Referring to the drawing, 1 designates the 50 cord of suitable length and gage, the ends being tied into knots 2 for permanently retaining the button or winder A on the cord. This button is made of wood or other suitable material and is preferably an elongated

body of about two inches long and one-half inch in diameter with the ends tapered so 55 that it can be conveniently gripped as a handle. Extending through the winder A from one end to the other is a zigzag passage consisting of a transverse portion 3 adjacent the center thereof and extending entirely 60 through the same are inclined portions 4 extending from the ends of the portion 3 to the extremities of the winder, there being openings 5 where the portions 3 and 4 of the passage connect and terminal openings 65 6 at the ends of the winder. These openings permit of the ready threading of the cord through the winder, and by making the passage in the form described, the cord passes over relatively sharp angles or corners 7 so 70 as to retard the free movement of the cord through the winder for the purpose of enabling the top to be wound with the required tension.

In using the spinning device, the winder 75 A is moved along the cord to a point adjacent one of the knots and the cord is applied to the top in the usual manner while one hand holds the winder A as a handle, and the other hand holds the top with the end 80 of the cord in proper position. The hand holding the winder is then given a rotary movement around the top so that the cord can be laid thereon in the usual manner, the cord passing through the winder as the latter is carried around the top. When the cord is fully wound, the winder is held in the palm of the throwing hand by the last three fingers while the thumb and first finger hold the top in the usual manner for 90 the throwing thereof. With a top spinning device of this character, the fingers do not become sore as is usually the result and the cord can be wound on the top with uniform tension and very quickly. 95

Having thus described the invention, what I claim is:

A top spinning appliance comprising an elongated body tapered at its ends and provided at a central point with a transverse 100 opening, and at opposite ends with longitudinally inclined openings which communicate at their inner ends with the respective opposite ends of the transverse opening, the outer ends of the longitudinally inclined 105 openings extending centrally through the

extremities of the body, and the inner ends of said longitudinally inclined openings extending through the sides of the body near the transverse opening, and a cord passed through the openings of the body and held frictionally therein, and provided with stops at its ends.

In testimony whereof I affix my signature in presence of two witnesses.

CHARLES C. TANNERT.
